UNITED STATES PATENT OFFICE

2,547,888

REVERSIBLE CRUSHER WITH TRAVELING BREAKER PLATES

Leslie A. Rhodes, Upper Arlington, Ohio, assignor to The Jeffrey Manufacturing Company, a corporation of Ohio

Application April 16, 1947, Serial No. 741,845

6 Claims. (Cl. 241—186)

1

This invention relates to a reversible crusher, and an object of the invention is to provide an improved reversible crusher, preferably one having rectilinearly traveling breaker plates forming opposite side walls of a crushing chamber in which the breaker plates are sloped downwardly and inwardly so as to provide a wide feed opening or inlet leading to the reducing chamber, thereby to prevent arching and clogging of the chamber feed inlet, particularly with certain types of materials.

A further object of the invention is to provide a reversible crusher of the above mentioned type in which guide chute means is provided to guide the material selectively to one side of the rotor or crusher chamber or the other, depending upon the direction of rotation of the rotor.

Other objects of the invention will appear hereinafter, the novel features and combinations being set forth in the appended claims.

In the accompanying drawings,

Fig. 1 is a side elevational view of a crusher incorporating the features of my invention; and

Fig. 2 is a sectional elevational view through the crusher of Fig. 1.

The embodiment of my invention herein disclosed includes a main frame 10 which is generally symmetrical and includes a pair of side frame members 11 which are built up or fabricated from a plurality of plates, angles and the like and which are connected together by transversely extending frame members, all of which cooperate to provide a generally symmetrical reducing chamber 12 located at the center of the crusher. The sides of the reducing chamber are preferably lined with removable liners 13 and, as illustrated in Fig. 1 of the drawings, each of the side frame members 11 includes a pair of outwardly swinging doors 14 which are normally closed and form a part of said side frame members. The top central portion of reducing chamber 12 is provided with a large or wide feed opening 15 which is located centrally of the unit and above and centrally of the feed chamber 12.

Extending transversely of the unit and through the side frame members 11 is a shaft 16 mounted at opposite ends in appropriate journal bearings 17 carried on the bottom portion of the main frame 10. A reversible rotor 18 is mounted on the shaft 16 and is preferably formed of a plurality of spaced discs and pivot swing hammers 19 carried on axially extending pivot rods 20. The axis of the rotor 18 and shaft 16 is preferably through the center of reducing chamber 12. Between each of the side walls provided by

5 the side frame members 11 and liners 13 and on opposite sides of the rotor 18 and forming opposite side walls of the reducing chamber 12 is a pair of similar endless rectilinearly traveling breaker plate assemblies 21 which are of similar construction and therefore the individual parts of them will be given similar reference characters. Each of said breaker plate assemblies 21 includes a frame 22 carrying an upper drive shaft 23 which is journaled in bearings 24 provided with take-up mechanism 25 to adjust the position of the shaft 23.

10 Adjacent its lower end the frame 22 is provided with an idler shaft 26. Shafts 23 and 26 are provided with sprockets 27 and 28, respectively, upon which a very heavy endless chain type breaker plate 29 travels, preferably in the downward direction, as indicated by the arrows in Fig. 2 of the drawings. As indicated in Fig. 2 15 of the drawings, the construction of each of the endless chains 29 is such that each effectively forms a substantially solid breaker surface against which material is knocked by the hammers 19 of the rotor and reduced. The take-up mechanism 20 25 provides for maintaining the endless chain breaker plate 29 in proper tension. This chain is driven through the drive shaft 23 and drive sprockets 27, said shaft 23 being in turn driven through a speed reducing mechanism 30 from an electric motor 31, which motor and speed reducing mechanism are mounted on a platform 32. It is obvious that there will be a separate driving motor and speed reducing mechanism for each of the chain breaker plates 29, there being 25 one on each platform at opposite sides of the machine.

30 As best seen in Fig. 1 of the drawings, the upper end of each frame 22 is mounted for limited swinging movement in the main frame 10 by virtue of a plate 33 at each side which is normally flush with the adjacent side frame member 11 and is provided with an arcuate bottom bearing surface 34 which fits on a cooperating arcuate bearing surface provided in the bottom of a notch 35 formed in the adjacent plate of the side frame 35 member 11.

40 Each end of each shaft 26 is journaled in a bearing 38 which is carried in a guide 36 formed on the bottom of a frame member 11 and is adjustable so as to swing the lower end of the frame 22 and thus the lower end of the traveling breaker plate 29 about the axis of the upper shaft 23, thus adjusting the breaker plate 29 45 toward and from the rotor 18. This, of course, 50 also adjusts the bottom opening 37 of the re-

ducing chamber 12 through which the reduced material is discharged therefrom.

Adjusting mechanism 39 is provided for each bearing 38 to adjust its position in the guide 36, thereby providing for the aforementioned adjustment and also providing for locking the breaker plate assembly 21 in position. Obviously each breaker plate assembly 21 may be individually adjusted in all of its various adjustments.

Mounted centrally of the intake or feed opening 15 and thus directly above the axis of rotation of the rotor 18 is an inverted V-shaped trough-like or peaked chute, deflector or feed guide 40 and this preferably cooperates with a shiftable flap or butterfly valve 40' in a chute, thereabove so that the material delivered to the crusher is selectively fed to one side or the other of the feed chamber 12 and the rotor 18, depending upon the direction of rotation of said reversible rotor 18. For example, if the rotor 18 is rotating in a counter-clockwise direction, as viewed in Fig. 2, the material will preferably be fed to the left-hand side of the feed chamber 12.

The feed chute 40 is so positioned and has such a spread relative to the diameter of the rotor 18 that material on being struck by one of the hammers 19 will be given a generally downward path as indicated by the broken line A in Fig. 2 of the drawings. In other words, it will preferably have no upward component of movement, but its vertical component will be downward. After the initial fracture of the material by being struck by a hammer 19, it will be impelled to the left, in the illustration under discussion, and be first thereafter broken by the left-hand rectilinearly traveling chain breaker plate 29. The impact of this material is preferably transmitted to the frame 22 through a reinforcing and wear plate 41 forming a part thereof.

It is to be particularly noted that the downward rectilinearly traveling breaker plates 29 slope downwardly and inwardly so that the feed opening 15 and each branch thereof, which is formed by the chute or guide 40, is a relatively large opening, while the discharge opening 37 is relatively small. Of particular importance is the provision of the wide openings or maws leading to the reducing chamber 12 because it has been found when certain material is reduced, iron ore being an illustration, there is a tendency for it to arch and build up around the feed opening unless it is quite wide. This is particularly true if the hammers strike the material and impel it with a motion which has an upward vertical component rather than a downward vertical component. Therefore the downward component of movement imparted to the impelled material by the hammers 19 and the wide or large feed opening co-operate to provide an improved feeder, particularly when handling material which may tend to pack and arch and thus choke up the feed chute, which is a characteristic of iron ore.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. A reversible crusher including a frame providing a reducing chamber having a wide open top feed opening, a pair of spaced side rectilinearly traveling breaker plate means forming opposite sides of said reducing chamber, a reversible swing hammer rotor located centrally of said reducing chamber and between said pair of breaker plate means, said breaker plate means sloping inwardly and downwardly whereby they are spaced apart a maximum at the top and nearest said feed opening, and chute guide means above the axis of rotation of said rotor adapted to guide material selectively to one side or the other of said rotor as it is fed through said feed opening.

2. A reversible crusher including a frame providing a reducing chamber having a wide open top feed opening, a pair of spaced side breaker plate means forming opposite sides of said reducing chamber, a reversible swing hammer rotor located centrally of said reducing chamber and between said pair of breaker plate means, said breaker plate means sloping inwardly and downwardly whereby they are spaced apart a maximum at the top and nearest said feed opening, and chute guide means above the axis of rotation of said rotor adapted to guide material selectively to one side or the other of said rotor as it is fed through said feed opening.

3. A reversible crusher including a frame providing a reducing chamber having a wide open top feed opening, a pair of spaced side rectilinearly traveling breaker plate means forming opposite sides of said reducing chamber, and a reversible swing hammer rotor located centrally of said reducing chamber and between said pair of breaker plate means, said breaker plate means sloping inwardly and downwardly whereby they are spaced apart a maximum at the top and nearest said feed opening.

4. A reversible crusher including a frame providing a reducing chamber having a wide open top feed opening, a pair of spaced side endless chain traveling breaker plate means forming opposite sides of said reducing chamber, a reversible swing hammer rotor located centrally of said reducing chamber and between said pair of breaker plate means, said breaker plate means sloping inwardly and downwardly whereby they are spaced apart a maximum at the top and nearest said feed opening, and chute guide means above the axis of rotation of said rotor adapted to guide material selectively to one side or the other of said rotor as it is fed through said feed opening.

5. A reversible crusher including a frame providing a reducing chamber having a wide open top feed opening, a pair of spaced side endless chain traveling breaker plate means forming opposite sides of said reducing chamber, a reversible rotor located centrally of said reducing chamber and between said pair of breaker plate means, said breaker plate means sloping inwardly and downwardly whereby they are spaced apart a maximum at the top and nearest said feed opening, and chute guide means above the axis of rotation of said rotor adapted to guide material selectively to one side or the other of said rotor as it is fed through said feed opening.

6. A reversible crusher including a frame providing a reducing chamber having a wide-open top feed opening, a pair of spaced endless traveling chain means forming opposite sides of said reducing chamber and spaced substantially solid breaker plate surfaces therein, a reversible swing

hammer rotor located centrally in said reducing chamber and between said endless chain breaker plate surfaces, said breaker plate surfaces of said chains sloping inwardly and downwardly whereby they are spaced apart a maximum at their tops and nearest said feed opening and extend downwardly adjacent and below said rotor, and a peaked deflector substantially directly above the axis of rotation of said rotor and in said feed opening cooperating with a shiftable feed chute means thereabove for guiding material as it is fed by said feed chute means through said feed opening to one side or the other of said rotor depending upon the direction of rotation of said rotor, said breaker plate surfaces of said chains traveling downwardly.
